[57] CLAIM

The ornamental design for tire, as shown and described.

DESCRIPTION

FIG. 1 is a perspective view of a tire showing my new design it being understood that the tread pattern is repeated uniformly throughout the circumference of the tire as shown schematically by solid lines;

FIG. 2 is a front elevation view thereof; and

FIG. 3 is a side elevation view thereof on a reduced scale it being understood that the opposite side is a mirror image of that shown.

FIG. 1

FIG. 2
